UNITED STATES PATENT OFFICE.

CHARLES HANSEN, OF DAVENPORT, IOWA, ASSIGNOR TO DAVENPORT MACHINE & FOUNDRY COMPANY, OF DAVENPORT, IOWA, A CORPORATION OF IOWA.

DESIGN FOR A STREET-LAMP STANDARD.

Application filed March 2, 1925. Serial No. 12,532. Term of patent 14 years.

To all whom it may concern:

Be it known that I, CHARLES HANSEN, a citizen of the United States, residing at Davenport, in the county of Scott and State of Iowa, have invented a new, original, and ornamental Design for Street-Lamp Standards, of which the following is a specification, reference being made to the drawing, forming a part thereof.

In the annexed drawing Fig. 1 is an elevation of my new standard having the il-

luminating head shown in dotted lines; Fig. 2 is a cross-section substantially along the plane indicated by the line 2-2 in Fig. 1; and Fig. 3 is a similar cross-section substantially along the plane indicated by the line 3-3 in Fig. 1.

I claim:

The ornamental design for a street lamp standard as shown.

CHARLES HANSEN.
